CLAIM

The ornamental design for a tamper-resistant lid assembly, as shown and described.

DESCRIPTION

FIG. 1 is an upper perspective view of a tamper-resistant lid assembly according to the present design, the tamper resistant lid assembly presently shown in an assembled state between a cap portion and an attachment ring portion; FIG. 2 is a lower perspective view of the tamper-resistant lid assembly of FIG. 1;

FIG. 3 is a first elevation view of the tamper-resistant lid assembly of FIG. 1;

FIG. 4 is a second elevation view of the tamper-resistant lid assembly of FIG. 1;

FIG. 5 is a third elevation view of the tamper-resistant lid assembly of FIG. 1;

FIG. 6 is a fourth elevation view of the tamper-resistant lid assembly of FIG. 1;

FIG. 7 is a top plan view of the tamper-resistant lid assembly of FIG. 1;

FIG. 8 is a bottom plan view of the tamper-resistant lid assembly of FIG. 1;

FIG. 9 is an upper perspective view of the tamper-resistant lid assembly according to FIG. 1, the tamper-resistant lid assembly presently shown in a disassembled state between the cap portion and the attachment ring portion;

FIG. 10 is a lower perspective view of the tamper-resistant lid assembly of FIG. 9; and,

FIG. 11 is a bottom view of the cap portion of the tamper-resistant lid assembly of FIG. 9, shown separately to depict aspects of the present design not visible when combined.
